UNITED STATES PATENT OFFICE.

GOTLEB VON ALMA, OF KILWORTHY, CANADA, ASSIGNOR OF ONE-HALF TO
GEORGE HUGHES AND JOHN E. HUGHES, OF SAME PLACE.

FRUIT-PICKER.

SPECIFICATION forming part of Letters Patent No. 642,541, dated January 30, 1900.

Application filed August 14, 1899. Serial No. 727,119. (No model.)

To all whom it may concern:

Be it known that I, GOTLEB VON ALMA, a citizen of the Swiss Republic, residing at Kilworthy, in the county of Simcoe, Province of Ontario, Canada, have invented certain new and useful Improvements in Fruit-Pickers; and I do hereby declare that the following is a full, clear, and exact description of the invention, such as will enable others skilled in the art to which it appertains to make and use the same.

This invention relates to fruit-pickers; and its object is to provide a device of this character which may be adjusted to any height without detaching the lower end from the barrel or other receptacle for the fruit. A further object is to provide a fruit-picker which is simple in construction, effective in operation, and economical to manufacture.

To these ends the invention consists in a fruit-picker constructed substantially as hereinafter illustrated and described, and defined in the appended claims.

The drawing shows a perspective view of the improved fruit-picker complete and in operative position.

A great objection to the ordinary fruit-picker is the necessity of carrying a receptacle for the fruit from place to place whenever the position or elevation of the device is changed. This necessitates at least one additional assistant and the extra labor involved in moving partially-loaded barrels. The device embodying this invention obviates these objections.

The body portion of the fruit-picker is constructed of two telescoping sections A and A', of which the part A is the receiver and is provided with an enlarged upper end *a* and a funnel-shaped extension *a'*, the lower end of which is sleeved in and telescopes with the funnel-shaped portion A'. The two sections A and A' are preferably made of canvas, though any durable flexible material will answer as well. The upper edge of the enlarged portion *a* is provided with a hoop *a²*, whereby it is distended, and from the edges of this hoop a series of ropes *a⁴* radiate to a ring *a³* in the center of said portion *a*. A series of openings *a⁵* are formed in the body of

the enlarged portion *a*, through which pass a series of ropes *a⁶*, which are attached to the upper edge of the funnel-shaped section A'. These ropes *a⁶* pass upward through the openings *a⁵* into the inner portion of the part *a* 55 and are led through the ring *a⁴* over a pulley *b*, mounted in the end of the extensible bar or handle B, and are connected at their extremities to an operating-rope *b*. The portion A' is made of any desired length, and the 60 lower edge thereof is provided with a hoop or ring. (Not visible in the drawing, as it is on the inside.) To this hoop are attached a series (preferably four) of wires or metal bands *a⁷*, which support a circular disk *c*, upon the 65 upper surface of which is secured a cushion or pad *c'*. The section A is provided with a metal hoop *a⁸*, which encircles the handle B and by which it is secured thereto. Supporting-rods *a⁹* are secured to the hoop *a⁸* and the 70 handle B, which serve to steady the section A.

The handle B is preferably made of two or more sections joined together in any suitable manner. The end of the handle is preferably provided with a rake for detaching the fruit 75 and which is useful for raking up the fallen fruit. A suitable cleat *b²* or other fastening device is fixed to the handle B for securing the adjusting-rope *b'*.

From the above description it will be seen 80 that by drawing in or letting out the rope *b'* the lower section A' may be raised or lowered, as may be necessary.

When the fruit is detached by means of the rake, it falls into the enlarged portion *a* of 85 the receiving-section A and strikes against the ropes *a³*, through which it passes after its fall has been somewhat arrested. The fruit then passes down through the funnel portion *a'* to the lower section A' or to the cushion *c'*, 90 which is located in the receiving barrel or bin, (not shown,) and passes out between the bands or wires *a⁷* without injury.

While I have herein shown a preferred form of carrying my invention into effect, yet I do 95 not desire to limit myself to such preferred details of construction, but claim the right to use any and all modifications thereof which will serve to carry into effect the objects to be obtained by this invention in so far as such 100

modifications and changes may fall within the spirit and scope of my said invention.

I claim—

- 5 1. A fruit-picker, comprising a telescoping body portion, a supporting-handle therefor, adjusting-ropes secured to said body portion and attached to said handle, substantially as described.
- 10 2. A fruit-picker, comprising an upper section, a lower section telescoping therewith, a supporting-handle secured to said upper section, and adjusting-ropes secured to said lower section and passing through the interior of the upper section and attached to the said handle, substantially as described.
- 15 3. A fruit-picker, comprising an upper sec-

tion having an enlarged top and a funnel-shaped lower portion, ropes attached to the edges of said top and to a ring arranged in the center thereof, a lower telescoping section, a handle, adjusting-ropes secured to said lower section, leading into said upper section and through said ring and attached to said handle, and a cushion secured to the bottom of said lower section, substantially as de- 20 scribed. 25

In witness whereof I have hereunto set my hand in the presence of two witnesses.

GOTLEB VON ALMA.
